CARPET, RUG, AND RUNNER FASTENER

Henry N. Gundelach, New York, N. Y.

Application June 12, 1929. Serial No. 370,323

6 Claims. (Cl. 24—224)

This invention relates to fasteners, and particularly to fasteners for securing carpets, rugs and runners to a floor or other surface so that they will normally remain in position but may be quickly removed at any time.

An object of the invention is to provide an improved fastener for carpets, runners and rugs which may be readily applied and removed, and which, when applied, presents a structure which cannot be seen but which may be readily disengaged at any time.

Another object of the invention is to provide a fastener with one part adapted to be permanently connected to the floor or other support and the other part connected to a rug or other member and the respective parts so formed as to readily interlock and be held in an interlocked position by the tension on the rug or other article. All these and other objects as suggested herebelow are attained by the means now to be described, and illustrated in the accompanying drawing, in which

Figure 1 is a plan view of part of a rug with an embodiment of the invention shown applied thereto;

Figure 2 is a top plan view of the fastener shown in Figure 1, the rug being eliminated and part of a floor or other support shown;

Figure 3 is a view similar to Figure 2 but with the parts shown in a different position;

Figure 4 is a sectional view through Figure 1 on the line 4—4, the same being on an enlarged scale;

Figure 5 is a plan view of the floor piece shown in Figure 3;

Figure 6 is a perspective view of the rug engaging piece shown in Figure 3;

Figure 7 is an edge view of the floor piece shown in Figure 5.

Like numerals refer to like parts throughout the several views.

Referring to the accompanying drawing by numerals, 1 indicates a floor or other support, and 2 a rug, runner or carpet. In placing any of these articles on a floor some means are desirable to hold the edges down and prevent movement. Heretofore tacks and other fastening means were used, but many of the fastening means were objectionable, because of the difficulty in placing them in position or removing them. In the present instance a fastener has been provided which should be carefully placed in position when first applied, and afterwards the rug or other article may be quickly applied or

removed, as the securing of the fastener is left unmolested.

In producing a fastener embodying the invention a floor piece or plate 3 is provided, and this

is secured to the floor 1 by suitable means, as 60

for instance, nails or screws 4. Plate 3 is merely a thin piece of sheet metal shown in Figure

4. This sheet metal is provided with apertures

5 for receiving the nails or screws 4 and with

a turned-up abutment or stop 6. This abutment 65

or stop is provided with under cut portions 7, as

shown in Figure 7, whereby it may properly in-

terlock with the rug piece 8 shown in detail in

Figure 6. The rug piece is formed from a single

piece of sheet metal stamped out in a certain 70

manner, so that the parts will be as shown in

Figures 3 and 6 when in use. This rug piece

includes inwardly-extending prongs 12, origi-

nally bent as shown in Fig. 6, and adapted by

pressure through the rug from above to be con-

cealably secured within the rug. In forming the

piece 8 a base or body 9 is provided, and in this

body a cross-shaped opening 10 is formed, where-

by the stop 6 may be readily inserted and the

parts moved over to a position shown in Figure 3, 80

so that the parts cannot be disengaged until the

rug piece 8 has been moved, whereby the stop

6 will be opposite the notches 10'. In forming

the rug piece 8 walls 11 are turned up from the

body 9, and these walls merge into corner pieces 85

12, above mentioned which are pointed and

which are preferably provided with a spear or

hook 13, whereby they cannot be readily with-

drawn from the rug 2. In order to prevent ac-

idental withdrawal the upper ends of the cor-

ner pieces 12 are turned over as shown in Fig-

ure 4. This turning over or clinching of the

corner pieces positively connects the piece 8 to

the rug, while the nails or screws 4 positively

secure the piece 3 to the floor. In this way the

parts are properly held in their set position and

may be interlocked or disengaged by a back and

forth sliding movement of the piece 8, as indi-

cated in Figures 2 and 3.

In order to prevent accidental disengagement 100

of members 3 and 8, the abutment 6 is resilient-

ly held in substantially the position shown in

Figure 3 by the spring 14. This spring extends

beneath the turned-over flange 15 and around

two corners beneath the ears 16 and 17. From

the ears 16 and 17 the spring merges into loops

18 and 19, as shown in Figures 2 and 3, said

loops overlapping part of the abutment 6. As

the loops 18 and 19 are rounded, the abutment

may be forced into the position shown in Fig-

110

ure 3 or removed therefrom by an appreciable pull, so that the parts may be engaged or disengaged, but when engaged will resist accidental disengagement. The spring and associated parts just described have been found to be a desirable structure, but if preferred, some other kind of spring may be used, provided it functions to resiliently hold the abutment 6 and associated parts substantially in the position shown in 10 Figure 3.

Where the device is to be used on a rectangular rug preferably four devices are used, one near each corner, the fasteners being spaced properly to maintain the rug under some slight tension. This will prevent wrinkles in the rug and hold the rug in the desired place. It will be evident that a greater or less number of fasteners could be used on a rug, and any desired number may be used on a runner or carpet. 20 However, when the fastener is used the same is positioned beneath the rug or other article, except for the upper ends of the post 12, which appear rather distinctly in Figure 1 of the drawing, but in the case of a rug or carpet the pile 25 will overlap the bent-over portions so that these members will not be seen and yet the device will function in the usual manner.

It is to be understood that the present disclosure is for the purpose of illustration only, and that the invention is not limited thereto. To those skilled in the art, many modifications of the invention will be readily apparent, and it will also be obvious to such skilled persons that part of the means may be used without other 30 parts thereof, many such combinations readily suggesting themselves. Therefore, it should be and is to be distinctly understood that for a definition of the limitations of the invention, reference must be had to the appended claims.

40 What I claim is:—

1. A fastener for carpets, rugs, and runners, comprising a plate adapted to be connected to a floor or other support, and a member having clinchable prongs normally extending inwardly 45 toward the center of the member, adapted to be concealably connected to the underside of the carpet, rug, or runner by pressure from above, the carpet or rug being of such thickness and the prongs of such length and formation as to 50 result in such concealment, said member being formed with means adapted to interlock with said plate, and means for preventing accidental disengagement of said member and said plate.

55

60

65

70

75

2. A fastener of the character described, comprising a floor plate having raised undercut extensions, and a rug member having means adapted to interlock with said extensions of the floor plate, said rug member having a plurality of upstanding prongs normally extending inwardly toward the center of the plate and adapted to extend through the lower or base portion of the rug or other article and be concealably clinched thereto, the rug being of such thickness and the prongs of such length and formation as to result in such concealment, and resilient locking means carried by said member for locking the same resiliently to said floor plate, said under-cut extensions being adapted to hold said locking member in operative position. 8

3. A fastener of the character described, including a rug member formed with a body having a T-shaped opening, a plurality of posts normally extending inwardly toward the center of said member, each post having a spur, and a floor member having raised undercut extensions adapted to engage in the narrow part of said opening for holding the two members together in functioning position. 9

4. In combination, a plate, a plurality of upwardly-extending clinchable projections secured in spaced relation around the edge of the plate, said projections being bent inwardly towards the center of the plate and having arrow-like ends 10 and being adapted to be clinched or bent by pressure from above into any sheet material to secure said plate from below to said sheet material. 10

5. The invention as in claim 4, including fastening means adapted to be secured to a floor and to be secured to the plate for attaching it to said floor. 110

6. The combination in a device for fastening a carpet or rug to the floor, of a floor fastening member and a member removably connected thereto and having prongs normally extending inwardly toward the center of said member, adapted to be concealably clinched into the base of the carpet by being placed thereunder and the carpet pressed downwardly into the same, the carpet or rug being of such thickness and the prongs of such length and formation as to result in such concealment. 115 120 125
